UNITED STATES PATENT OFFICE.

ELIOT KEEN, OF NEW YORK, N. Y., ASSIGNOR TO TELEGRAVURE COMPANY, A CORPORATION OF NEW YORK.

TELEGRAPHY.

1,176,147.

Specification of Letters Patent. Patented Mar. 21, 1916.

Application filed November 6, 1908. Serial No. 461,335.

To all whom it may concern:

Be it known that I, ELIOT KEEN, a citizen of the United States, residing in the borough of Manhattan, city, county, and State 5 of New York, have invented certain new and useful Improvements in Telegraphy, of which the following is a specification.

My invention relates to the art of reproducing pictures at a distance electrically, 10 and comprises certain improvements in an apparatus for this purpose and particularly adapted for the carrying out of the novel process of my invention for transmission of pictures electrically.

15 In my process I propose to use a half-tone cut or negative of the picture, or its equivalent, from which, by means of suitable apparatus, I produce a series of electrical impulses proportioned to the size of the several dots composing the half-tone, either by 20 making and breaking the electrical circuit at every dot, or by varying the current strength in the circuit, the former method being preferred. At the receiving station, 25 which may be located at any point in the electrical circuit, suitable mechanism controlled by the electrical impulses is provided for reproducing the picture or half-tone. This is preferably accomplished by producing 30 a series of dots located in the same relative positions as the dots of the original half-tone and through the electrical impulses proportioned in area to the sizes of corresponding original dots. A half-tone 35 picture of exactly the appearance of the original half-tone is thus produced.

I have illustrated in detail certain specified sending and receiving apparatus by which my process may be carried out, but I 40 do not desire to be limited thereto, as I may use any desired sending apparatus which will produce a varying electrical impulse or series of impulses proportioned to the tones of a picture with my improved receiving 45 apparatus, whereby certain of my process improvements will be utilized, or I may use any form of receiving apparatus which will produce half-tone dots proportioned to the size of dots at the sending station, or to the 50 tone values of certain particular portions of the sending picture. Certain of my improvements may also be utilized in other relations.

I do not claim my improved process or processes in this application, neither do I 55 claim the apparatus for performing such processes in its broadest aspects. Such processes and apparatus are claimed broadly in my application Serial Number 548,047 filed March 8th, 1910. In the present case the 60 invention claimed relates to certain features of construction not illustrated or not claimed in said application, but which are applicable to the carrying out of the inventions therein broadly set forth and claimed, 65 some of the features, however, being also useful in other relations.

In the accompanying drawings Figure 1 is a plan view of a sending apparatus embodying certain of my improvements, parts 70 of the apparatus being shown in section; Fig. 2 is a plan view of a receiving apparatus; Fig. 3 is a transverse section of the receiving apparatus shown in Fig. 2; Fig. 4 is a detailed side elevation showing gearing 75 for operating the diaphragm mechanism; Fig. 5 is a detailed view of the diaphragm mechanism of the receiving apparatus; Fig. 6 is a detailed view of my selenium sending element; Fig. 7 is a front elevation of the 80 movable screen forming part of the sending mechanism; Fig. 8 is a horizontal section through the casing for the selenium sending element, showing the latter in plan; Fig. 9 is a diagrammatic view of a pair of dia- 85 phragms having graduated holes therein; Fig. 10 is a view illustrating an arrangement of diaphragms with a shutter for controlling the passage of light in the aperture between the diaphragms; and Fig. 11 is a 90 diagrammatic view illustrating the arrangement of the mirror so as to produce a positive instead of a negative record.

Referring to the drawings in detail, the numeral 1 designates the transparent hollow cylinder of the transmitting apparatus in which is a mercury tube light 2, or any other suitable source of illumination. Suitable connections for supplying electricity to this light may be used, such as those indicated at 3, 3. The cylinder 1 is rotated about its axis by means of a motor 4 through a series of gears 5 and 6. Simultaneously with this rotation a carriage 9 is moved parallel to the axis of the cylinder 1 by means 100 of a screw 8 rotated from the motor 4 in

any suitable manner, as by a gear 7 meshing with a gear 6. Guide bars 10 serve to support the carriage 9. The carriage 9 engages with the screw 8 by means of a split nut 11, 5 which may be opened and closed by a screw 12 to permit adjustment of the carriage 9. The pitch of the screw 8 and the gears 6 and 7 are so proportioned that the carriage 9 will move longitudinally a distance equal 10 to the distance between two of the rows of dots forming the half-tone carried by the cylinder 1, and designated by the numeral 1^a, while the cylinder 1 makes a single revolution. The dots forming the half-tone will 15 thus be brought successively opposite the aperture 30 in the screen 30^a forming the front of the chamber 23 carried by the carriage 9. The position of the chamber 23 which is pivoted to the carriage at 27, may 20 be adjusted by means of a screw 28.

Back of the aperture 30 in the chamber is a lens 31 which diffuses the light coming through the aperture throughout the chamber. In the rear part of the chamber is a 25 fixed diaphragm 22 provided with an aperture 22^a. In the rear of the chamber back of this diaphragm is mounted a disk 20 carried by a rotatable shaft 17 and bearing upon its front face a ring 19 of selenium 30 wire or its equivalent. The disk 20 and the selenium ring 19 are so positioned that a portion of the ring will always be exposed back of the aperture 22^a. A pair of conducting brushes or contacts 24 and 25 are 35 mounted on the rear face of the diaphragm 22, the disk 20 being forced toward these contacts so that the ring 19 will be held in electrical connection therewith by means of a spring 21. The shaft 17 and the disk 20 carried thereby are rotated slowly by any suitable means such as the gear 16 on the end of shaft 17 engaged by the gear 15 mounted on the shaft 14. On the other 40 end of shaft 14 is a pinion 13 engaging with rack-teeth 10^a cut in the face of guide bar 10. As will be obvious, when the carriage 9 is fed longitudinally by the screw 8, the pinion 13 which moves therewith will be 45 rotated through its engagement with the fixed rack-teeth 10^a.

The operation of this mechanism is as follows: The light through the lamp 2 passes through the transparent cylinder 1, and through the transparent portions of the half-tone negative 1^a; as the successive transparent portions or dots on this negative register with the aperture 30 in the screen 30^a, the pencil of light will pass through the aperture and be diffused by the lens 31 into 55 the chamber 23 from which a portion of it will pass through the aperture 22^a upon that portion of the ring of selenium 19 exposed between the brushes 24 and 25. The effect 60 of the exposure of the substance selenium

to light is, as is well known, to greatly increase its conductivity. Selenium when not exposed to light is a very poor electrical conductor. The circuit 26 which includes the brushes 24 and 25 is closed through that portion of the selenium ring exposed between the edges of the brushes. The length of the exposure of this portion of the selenium to the light depends on the size of the transparent dot on the half-tone negative, being a short time for a small dot and a longer time for a large dot. The object of the mechanism for rotating the disk 20 and the selenium ring is to continue to present a fresh portion of selenium to the action of the light, that is, to have practically a new selenium cell for each dot. By this means the objection due to the inertia of the selenium cell,—that is, its tendency to remain a conductor for a time after it is no longer exposed to the beam of light, is obviated. The circuit 26 is preferably a local circuit and operates the relay 32 which closes the main line circuit 33. A circuit 35 supplies electricity to the motor 4, 34 being a switch for controlling the same. 90

Referring now to the receiving machine shown in Figs. 2 and 3, the main circuit 33 which is opened and closed by the relay 32 in the manner described, once for every dot on the half-tone negative, contains at the receiving end a relay 34^a which opens and closes a local circuit 35^a. In this circuit 35^a is an electro-magnet 60, the armature 59 of which is preferably made in the form of a bell-crank and bears on the free arm thereof a mirror 36. The spring 61 serves to draw the armature away from the magnet when the circuit is broken. 37 is a source of light adapted to be reflected by the mirror 36 and directed by the latter toward the picture reproducing mechanism. This mechanism comprises a light-proof casing 58 enclosing a cylinder 54, to which is secured a sensitized film 38. A key 64 fitted in a slot in the cylinder may be used for the latter purpose, the edges of the film being wedged into the slot beneath the key. The cylinder 54 is mounted upon a shaft 53, one end of which is screw-threaded as shown at 55, and rotates in a screw-threaded bearing or nut 56. The other end of the shaft is slotted as shown at 56^a and passes through the nave of the gear 52 which is provided with a feather sliding in the slot. The gear 52 is driven through a gear 49 and pinion 50 from a motor 51 which receives current from any suitable source, as from the mains 35. 57 is a controlling switch. The casing 58 is provided with an aperture 58^a in the same horizontal plane as the axis of the cylinder 54, 125 and in line with the mirror 36. The opening to this aperture is controlled by a shutter or diaphragm mechanism of such a na-

ture that a light opening will be formed which continually passes through a cycle increasing from zero or a minimum opening to a maximum, and then decreasing. As shown, this shutter mechanism comprises a series of four diaphragms 39. Diaphragm D is fixed, while diaphragms A, B and C are mounted on shafts 40 adapted to be rotated by gearing 41 and 42. Diaphragms A and B are mounted on their respective shafts with an equal eccentricity, while diaphragm C has, as shown in the particular embodiment of my invention illustrated, double the eccentricity of A and B. The gear 42 which drives the diaphragms is mounted on a shaft 44 which is driven through screw gearing 43 and 45 from a transverse shaft 46. The shaft 46 is in turn driven through pinion 65, gear 48, pinion 66 from gear 49 which is driven, as has already been described, from the pinion 50 of the motor 51. 62 and 63 are lenses for concentrating the light reflected by the mirror 36 upon the sensitized surface 38. The motors 4 of the sending apparatus and 51 of the receiving apparatus are arranged to drive the cylinders 1 and 54 at identical angular velocities. Any suitable means for synchronizing these motors may be used, as for instance, they may be synchronous alternating current motors driven from the same alternating current circuit.

The operation of the reproducing mechanism is as follows: The cylinder 54 carrying the film 38 being rotated by the motor 51 at an angular velocity equal to that at which the cylinder 1 is rotated, revolves about its axis and is also moved in an axial direction by the action of the screw 55 in the nut 56. The pitch of the screw 55 is so proportioned that the ratio of the axial velocity to the circumference of the drum is the same as the ratio of the velocity of the carriage 9 to the circumference of the cylinder 1. The gearing by which the shutter mechanism 39 is operated is so proportioned that the diaphragms A, B and C will make one revolution while a portion of the sensitized surface 38 equal in width to the width of the maximum dot which is to form reproduced half-tone passes the light aperture. If now it be supposed that a half-tone negative is placed about the cylinder 1, and adjusted so that the first transparent dot in the first column of dots forming this negative registers with the aperture 30^a, the light passing through this dot and through the aperture acts upon the exposed portion of the selenium ring, closes the local circuit and closes the main circuit in the manner already described; this in turn closes the local circuit 35^a at the receiving station and turns the mirror 36 to such a position that it will receive a beam of light from the source 37

through the lens 62, the aperture 58^a, and 65 whatever opening there is between diaphragms A, B, C and D, and finally through the lens 63 upon the sensitized surface 38. When the apparatus starts, the diaphragms A, B and C are turned to such a position 70 that they almost if not entirely shut off light passing through the aperture 58^a, the diaphragms gradually separating to expose a larger and larger portion of the sensitized surface. If the dot at the sending apparatus is small, the circuit will break when but a small opening has been found between the diaphragms, so that a dot of corresponding size will be recorded. As will be apparent in the sending half-tone, the centers of successive dots are equal distances apart regardless of the size of the dot, so that the impulse corresponding to a small dot will not start until later than the impulse sent by a large dot, as the small dot does not extend as far in front of the theoretical dot center as does a large dot. The diaphragms A, B and C each make a complete revolution during the time occupied by the drum 54 in moving a distance equal to the distance between the centers of two successive dots, so that if the diaphragms leave no opening at the center of one dot, they will have returned to that position of no opening at the center of the next dot. If it be supposed that a 95 dot of considerable size is now being sent, it will be seen that the circuit 38 will remain closed longer than in the case of the sending of a small dot, and also that this closure will come earlier and extend later; thus, at 100 the beginning of the impulse, the diaphragms will not have moved to such a position as to practically close the opening between them, but will leave an opening of considerable size, corresponding to the size of the dot on 105 the sending half-tone. This exposure continues while the opening between the diaphragms grows smaller and smaller, until the minimum is reached and passed, when the opening between the diaphragms will 110 gradually increase in size. Simultaneously, however, with the reaching by the opening of a size corresponding to that of the sending half-tone dot, the impulse will cease and the mirror 36 will throw the beam of light away from the aperture so that the exposure will come to an end. A photographic record will thus be produced upon the film 38 exactly proportional in size to the area of the sending half-tone dot. The reason 115 for having one of the diaphragms stationary, as shown at D, is that the rotation of the drum carrying the film 54, continually exposes past the edge of this diaphragm a fresh film surface, producing the same effect 120 as if the film were stationary and the diaphragm D moved relatively to it.

It is obvious that the forms and propor-

tions of the diaphragms or other means used for forming the aperture for admitting light to the recording sensitized film, including the degree of eccentricity of the movable diaphragms, may be varied to produce an aperture of desired shape, usually such an aperture as will produce a substantially square dot upon the film. The portions of the diaphragms are preferably such that all of the dots produced will be symmetrical in outline regardless of their size.

I do not limit myself to the particular number of diaphragms shown, as the same or a similar result may be obtained by the use of modified apparatus such as an arrangement of two diaphragms which engage or overlap each other, each of the diaphragms being provided with a row of graded holes. Such a construction is illustrated diagrammatically in Fig. 9, in which a pair of diaphragms 100 and 101 are provided which rotate in opposite directions about the axes 102 and 103, respectively, these two diaphragms overlapping and being provided with rows of graduated holes 104. The diaphragms rotate in the direction of the arrows, and, at the same time, speed so that an aperture 105 will be formed by the registration of corresponding holes in two diaphragms. The smallest holes register first, and, as the diaphragms revolve, successively larger holes come into registration so that the effect of an aperture gradually increasing in size is produced. These diaphragms are placed in the same relation to the source of light and sensitized surface as the diaphragms A B C and D shown in Fig. 5, and the operation is essentially the same. It is also obvious that I may make a variety of other changes and modifications in the specific apparatus shown: for instance, I may use in place of the oscillating mirror a shutter for controlling the admission of light to the sensitized recording surface.

In Fig. 10 I have shown a modified construction in which a shutter is utilized in place of the oscillating mirror. This figure shows the four diaphragms A', B', C' and D' forming the aperture between them, the diaphragm B' being provided with an extension 106 which acts to cover the aperture which would otherwise be formed between the diaphragms during the time that such aperture is decreasing from maximum to zero. In other words, the aperture starts from zero and increases to maximum and is then closed during the other half revolution of the diaphragms. The shutter for cutting off the light from the aperture is indicated at 107, it being preferably mounted upon the end of arm 108 pivoted at 109. The arm carries the armature 110 which is adapted to be acted upon by the magnet

111 during the time that the impulse is coming over the line so as to permit the light to pass through the aperture and make a record of the impulse. When the impulse ceases and the magnet 111 is deenergized, the shutter is released and is quickly drawn into a position to close the aperture by the spring 112. In order to restore the shutter to such a position that the armature 110 will be within the influence of the magnet 111, a cam 113 is used, this cam being mounted upon a shaft of the disk B' and acting upon the stop 114 on the shutter arm in such a way as to push the shutter open and bring the armature into proximity with the magnet. This is accomplished during the time that the aperture is closed by the extension 106, so that the exposure of the sensitized surface through the aperture is not affected. At the same time that the minimum aperture is opened between the diaphragms and by the movement of the extension 106 beyond the limit of the aperture, the shutter is restored to its open position with the armature adjacent to the magnet so that any impulse energizing the magnet will at once cause the latter to act upon the arm and retain the shutter open, as shown in Fig. 10. This condition continues so long as the impulse lasts, but as the cam 113 is now moved out of the way of the stop 114, as soon as the impulse ceases the shutter will close and cut off the light.

As will be apparent, I may produce at the receiving apparatus a picture which is a negative of the picture at the sending apparatus, that is, having a dot or exposed portion corresponding to every transparent dot of the sending half-tone, or I may make the record identical with the sending picture by changing the position of the mirror or shutter and the operating mechanism therefor so that the light will be cut off from the receiving surface at the times when the circuit is closed instead of when it is interrupted. Such an arrangement is illustrated in Fig. 11 in which the mirror is arranged to throw the beam of light through the aperture and upon the sensitized surface when the line is deenergized, while, when the impulse is upon the line and the armature contracted by the magnet, the mirror will be tilted so as to throw the beam away from the aperture, as indicated by the dotted line 120.

The words "half-tone" and "half-tone negative" are used herein for the sake of clear expression, but I do not intend thereby to limit myself to the use of the articles technically known by those names.

Having described my invention, I claim:

1. In apparatus of the class described, a sending apparatus, and a receiving apparatus, said sending apparatus comprising

- means for sending a series of impulses to said receiving apparatus, the lengths of said impulses corresponding to the tones of portions of a picture, said receiving machine 5 comprising a photo-sensitive surface, means controlled by said impulses for exposing successive portions of said surface to light, the light to which said surface is exposed passing through an aperture, and means for 10 continually and gradually varying the area of said aperture between maximum and minimum values.
2. In a machine for photographically reproducing at a distance half tones by the 15 operation of electrical impulses caused by and corresponding in relative frequency and duration to the dots of such half tones, a series of eccentrically mounted diaphragms, whose edges mutually engage each other, 20 which move at uniform speed, so that an aperture is constantly formed which increases steadily in size from zero to a fixed maximum and then at the same rate becomes zero again; and a means for admitting light 25 through said aperture by the operation of a shutter or mirror which is caused to oscillate by the several electrical impulses aforesaid, so that there are photographically produced on a moving sensitized surface to which 30 these operations admit the light, dots which correspond in size and relative location to the dots of the half tone which is being transmitted.
3. In a machine for photographically reproducing, from electrical impulses derived 35 from and related to each other as the dots of a half tone, dots corresponding in size and relative situation to the dots of the transmitted half tone, four circular dia- 40 phragms which engage each other, one of which is fixed, the other three of which move at uniform speed on eccentric bearings, said diaphragms opening and closing an aperture having four equal slightly con- 45 cave sides; in combination with a means actuated by the electric impulses produced from the original half tone, for permitting light to pass to a moving sensitized surface beyond the opening made by the moving diaphragms aforesaid.
4. In a telegraphic sending instrument, a selenium cell, means for intermittently exposing a portion of said cell to light at a fixed point, the duration of successive exposures and of the intervals between said exposures being governed in accordance with the impulse to be transmitted, an electric circuit adapted to be closed through a portion of the selenium of said cell, and means 55 for moving said cell progressively to cause a previously unexposed portion of selenium to replace that just exposed at said point of illumination.
5. In a telegraphic sending instrument, a selenium cell, means for intermittently exposing a portion of said cell to light at a fixed point, the duration of successive exposures and of the intervals between said exposures being governed in accordance with the impulse to be transmitted, an electric circuit adapted to be closed through a portion of the selenium of said cell, means for moving said cell progressively to cause a previously unexposed portion of selenium to replace that just exposed at said point of illumination and simultaneously withdrawing from said circuit the portion of the selenium which is replaced.
6. In combination with an electric circuit and a controlled source of light, a selenium cell comprising a selenium element, means for moving the same across the field of illumination whereby successive portions of the selenium element are exposed, and means for simultaneously withdrawing from the circuit that portion of the selenium element exposed at the point of illumination during the immediately preceding impulse.
7. In a selenium circuit closing device, a pair of contact brushes, a ring of selenium supported in contact with said brushes, and means for rotating said ring, that portion only of said ring which lies between the edges of said contact brushes being capable of exposure to light.
8. In a telegraphic circuit, a receiving device sensitive to changes in current intensity, and a sending device including an endless surface of material whose specific resistance is altered by exposure to light, and means for introducing a different portion of said surface into the circuit at each impulse originated therein and for removing from the said circuit the portion of said surface active during the immediately preceding impulse.
9. In a telegraphic circuit, a receiving device sensitive to changes in current density and a sending device including an endless surface of material whose specific resistance is altered by exposure to light, means for including in said circuit a continuously changing portion of said surface, but constant in length, and means for illuminating only that portion of said surface which is for the time being included in said circuit.
10. In a telegraphic machine operated by electrical impulses caused by and corresponding in relative frequency and duration to the dots of a half-tone, a series of eccentrically mounted diaphragms with mutually engaging edges, means for moving said diaphragms at a uniform speed to form an aperture constantly altering its area from zero to a fixed maximum and returning at the same rate to zero, and means for illuminating said aperture at controlled intervals.

to form a photographic record comprising dots exactly corresponding in proportionality and proportional location to the dots of the half-tone originating the impulse.

5 Signed at the city of New York, in the county of New York and State of New

York, this fourth day of November, one thousand nine hundred and eight.

ELIOT KEEN.
